UNITED STATES PATENT OFFICE.

ARTHUR O. BUSCH, OF FLASHER, NORTH DAKOTA.

SPRING-MOTOR.

1,123,241.

Specification of Letters Patent.

Patented Jan. 5, 1915.

Application filed January 12, 1914. Serial No. 811,664.

To all whom it may concern:

Be it known that I, ARTHUR O. BUSCH, a citizen of the United States, and a resident of Flasher, in the county of Morton and 5 State of North Dakota, have invented certain new and useful Improvements in Spring-Motors, of which the following is a specification.

This invention relates to spring motors 10 which are particularly adapted for fans which are actuated by springs and designed to move the air in inclosed spaces.

The principal object of the invention is to obtain a fan to move the air in a room, 15 chamber, hall or other inclosed space, which is actuated by a spring and which will run for a considerable time after being wound up.

A further object is to obtain a device 20 which will not require frequent oiling, and which will not produce a great amount of friction in the train of wheels actuated by the spring of the device.

A further object is to produce a device 25 which will present a good appearance; which is easily wound; which is not liable to break or get out of order, and which is portable.

In the drawings, which illustrate a device 30 embodying this invention Figure 1 is a vertical section of the shell and an elevation of the movable parts of said device. Fig. 2 is a side elevation of the cap of the shell and Fig. 3 is side elevation of the base of 35 said cap. Fig. 4 is a horizontal section on line 4—4 of Fig. 1, viewed in the direction indicated by the arrows. Fig. 5 is a top plan view of the gear train of the device and of the body of the box in which said train is 40 inclosed. Fig. 6 is a section on line 6—6 of Fig. 5, viewed in the direction indicated by the arrows.

A reference letter applied to designate a given part indicates said part throughout 45 the several figures of the drawing wherever the same appears.

X is the outer shell holding the movable parts of the device, X¹ is a base and journal bearing attached to the upper shell X, 50 and X² is a cap which fits on the base X¹.

Y is a fan shaft which is journaled in bearings Y¹ and Y², in base X².

Z is a vertical shaft journaled at its upper end in the journal bearing Z¹ in base X¹.

55 W is a beveled gear wheel on the upper end of shaft Z and W¹ is a beveled gear wheel

on fan shaft Y. The teeth of wheels W and W¹ intermesh so that the fan shaft is turned by the rotation of the vertical shaft.

U is a non-rotatable shell in which the 60 spring U¹ is contained; and V is a box or shell in which the gear train of the device is contained. Box or shell V is provided with a cover V¹, and said cover is provided with a journal bearing V² in which the lower end 65 of the vertical shaft Z is journaled.

V³ is a collar attached to the vertical shaft Z, and V⁴ are balls on which collar V³ rests and rides as it is turned by the turning of shaft Z. Shaft Z thus rests on said balls 70 and is supported thereby.

a is a gear wheel which is loosely mounted on the end of the hollow bearing a¹ of drum a². Drum a² is provided with an additional hollow bearing (a³) and both of said hollow bearings, (a¹ and a³) are journaled in the bottom and top plates of the shell U. The inner end of spring U¹ is attached to hollow drum a², and the outer end thereof is attached to the vertical wall of shell U. 75

Gear wheel a intermeshes with gear wheel A which is rigidly secured to shaft b. Shaft b is journaled at its upper end in step b¹ and at its lower end in bearing b² on the bottom of box or shell V. Step b is attached 80 to the upper face of the cover V¹ by rivets or bolts b³. Shaft b thus extends above the cover V¹ and passes through an aperture provided therefor, fitting said aperture reasonably close so that half hard grease or 85 oil in said shell V will not flow through said aperture.

C is a pinion on shaft d intermeshing with the teeth of gear wheel B. D is a gear wheel on said shaft d, intermeshing with 90 pinion E on shaft e.

F is a gear wheel on shaft e, intermeshing with pinion G on shaft g.

H is a gear wheel on shaft g intermeshing with pinion I on shaft h; and J is a gear 100 wheel on shaft h intermeshing with pinion K on vertical shaft Z.

It will be observed that the vertical shaft Z passes through the hollow bearings a¹ and a³ of drum a², and through the cover V¹ 105 of box or shell V. The aperture in said cover which is provided for the vertical shaft to pass through fits so closely to said shaft that no oil or grease will flow from box V around said vertical shaft. The several shafts d, e, g and h are journaled within the box V and do not extend through the 110

bottom or cover thereof, (see bearings f, f). L is an aperture in the bottom of box V through which oil or grease is introduced to nearly fill said shell. A plug, l, is fitted on to aperture L after oil or grease of a suitable consistency is introduced into box or shell V to fill or nearly fill said box.

M is a ratchet wheel on sprocket wheel N.

Backward rotation of the ratchet wheel M without corresponding movement of the gear train is prevented by pawl m which is pivoted on the upper face of wheel a. Hollow bearing a^3 is rigidly secured to the hub n of sprocket wheel N so that turning 15 of said sprocket wheel turns hollow drum a^2 and winds spring U¹. The unwinding of said spring actuates the above described train of gear wheels, thus rapidly turning vertical shaft Z and fan shaft Y. Sprocket 20 wheel N is turned by means of sprocket chain O, wheel P on shaft p, ratchet wheel p¹, and handle p², (which is provided with a ratchet p³ engaging with ratchet p¹).

Q are bosses on the under side of the bottom of shell V, adapted to receive bolts or screws q, to secure said shell V to the bottom of shell X. The attachment of the base X¹ to the shell X consists in placing the cir-

cular part or portion X³ of said base X in the upper circular end of shell X, (see Fig. 30 1). Said base X¹ can then be turned in a horizontal plane.

I claim:—

A casing, shells in said casing rigidly secured thereto, a hollow hub and a spring in 35 one of said shells, journal bearings to said hollow hub in the hub containing shell, means adapted to turn said hub in one direction to wind said spring and to permit said hub to turn in the opposite direction as said 40 spring unwinds, and a gear train in the other of said shells, in combination with a vertical shaft extending through said hollow hub and adapted to be driven by said gear train, bearings to said vertical shaft, one of 45 said bearings positioned above and one below said hub containing shell, and a connection comprising a ratchet, pawl and gear wheels between said hollow hub and said gear train, said gear containing shell adapted 50 to retain a fluid lubricant therein when said gear train is in operation.

ARTHUR O. BUSCH

In the presence of—

M. LINDBLOM,

C. D. MYERS.
